DRAFT RIGGING

Donald S. Barrows, Rochester, N. Y., assignor to
The Symington Company, New York, N. Y., a
corporation of Maryland

Application February 5, 1931, Serial No. 513,683

10 Claims. (Cl. 213—7)

This invention relates to railway draft rigging and, more particularly, to such associated with draft gears of the friction type, and so arranged that a greater amount of travel and cushioning effect is provided for the absorption of buffing forces than for the absorption of draft forces.

The principal object of my invention, generally considered, is to provide a preferably double-ended friction draft gear or cushioning device so associated with a vertical yoke and held in position by a horizontal supporting key which also functions as front stop means that the mechanism will function to provide a greater energy absorbing capacity for buffing forces than for draft forces.

Another object of my invention is to provide draft rigging involving a drawbar suitably connected to a vertical yoke which, in turn, embraces friction shock-absorbing mechanism adapted to resist movement of the drawbar under both buffing and draft, said mechanism being disposed between draft sills and held in position by a centrally disposed horizontal key passing through a slot in the mechanism housing and through corresponding slots in the draft sills, which sills are preferably reinforced by slotted cheek plates so that only part of the capacity of the mechanism is utilized for absorbing draft forces, while all acts to absorb buffing forces.

A further object of my invention is the provision of railway draft rigging comprising an operatively connected drawbar and vertical yoke, with a preferably double-ended friction draft gear disposed between the arms of the yoke and rearwardly of the drawbar, said mechanism being supported by transverse means, the ends of which are, in turn, supported by the draft sills of the associated railway vehicle, and the supported gear serving, in turn, for the support of the yoke, said gear preferably having spring and friction elements at each end, said friction elements being so interlocked with the gear housing that no means need be provided to hold them assembled with said housing when the coupler and yoke move forwardly under the action of draft forces.

A still further object of my invention is the provision of railway draft rigging involving a vertical yoke embracing a double-ended friction draft gear supported between the sills of the associated railway vehicle by means of a horizontal key, the ends of which are received in the slots in said sills, said key functioning as a front stop means for the cushioning mechanism in the rear end of the gear, so that said mechanism only is

actuated upon the application of draft forces, said gear comprising spring and friction elements at each end and associated followers, the front follower being prevented from floating forwardly out of position with respect to the gear when the associated coupler and yoke move away under the action of draft forces by diminutive lugs or front stop means preferably forming part of the striking casting of the vehicle, and/or the cheek plates which receive the coupler and yoke connecting draft key, said lugs being preferably normally spaced from the front of said follower to facilitate assembly.

Other objects and advantages of the invention relating to the particular arrangement and construction of the various parts will become apparent as the description proceeds.

Referring to the drawings illustrating my invention, the scope whereof is defined by the appended claims:—

Figure 1 is a partial, horizontal sectional view through the draft sills of a railway vehicle, illustrating one embodiment of my double-ended series draft gear or cushioning mechanism, with associated draft rigging and supporting key, the draft gear and associated vertical yoke being shown partly in plan and partly in horizontal section to more clearly illustrate the construction.

Figure 2 is a vertical, sectional view illustrating the embodiment of my gear and associated rigging shown in Figure 1, the associated yoke and said gear being shown partly in side elevation and partly in vertical section to more clearly show the construction.

Figures 3 and 4 are views corresponding, respectively, to Figures 1 and 2, but showing a modification.

Referring to the drawings in detail, like parts being designated by like reference characters, and first considering the embodiment of my invention illustrated in Figures 1 and 2, there are shown portions of a railway vehicle underframe comprising center or draft sills 1 connected by a rear draft lug casting or combined backstop and center filler casting 2 and a striking casting and sill tie member 3 at the ends thereof.

The sills 1 are slotted, as usual, for connection with associated draft rigging, and preferably have connected thereto cheek plates 4 which, in the present embodiment, are formed as rearward continuations of the combined striking casting and sill tie member 3. Said cheek plates are slotted at 5 with the slotted portions preferably rigidified by flanges 6 defining the edges of said slots to adapt said cheek plates for the transmission of

large forces. Disposed between the sills 1 and received in the opening 7 provided through the combined casting 3, is a drawbar or coupler stem 8 connected to a vertical yoke 9 by means of a horizontal key 10, the ends of which are received in the slots 5 in the cheek plates 4 for the support of said key and associated parts.

Disposed rearwardly of the drawbar 8 and embraced between the arms of the yoke 9 is a draft gear 11 of the double-ended type or involving a plurality of cushioning devices 12, one at each end thereof. The draft gear 11 comprises a housing or casing 13 formed with partitions 14 and a web 15 slotted, as indicated at 16, to receive connecting and supporting means 17, which, in the present embodiment, takes the form of a horizontal draft key, the ends of which are received in slots 18 in cheek plates 19 and/or the sills 1 of the vehicle. The partitions 14 provide compartments 20, one at each end of the housing, for receiving the cushioning mechanism 12, the outer ends of said compartments 20 being partially closed by flanges or webs 21, leaving, however, an opening 22 for receiving the mechanism 12 which, in the present embodiment, comprises resilient means or curved plate springs 23, friction shoes 24, only one of which is illustrated in Figure 1, and the double wedge member 25. The wedge member and shoes are shown formed with double cooperating friction surfaces and shoulders causing interlocking between the parts when in normal position, the outer or large end of the double wedge member 25 being preferably formed with an integral follower portion 26. Movement of the wedge member 25 is limited by forming a slot 27 in the double wedge portions thereof and slots 28 in the upper and lower walls of the housing 13, and inserting a key 29 through said slots 27 and 28, said key being desirably retained in position or interlocked by engagement between a lug 30 on the wedge 25 and a notch 31 in said key. The necessary inward movement of the wedge 25 at each end of the housing is permitted by the outward elongation of the slot 27. It will be understood that although the mechanism at only one end of the housing is illustrated, corresponding mechanism is preferably used at the other end. Because of this keyed connection, the cushioning mechanism is self-contained with respect to the housing and will stay in place, as shown in Figure 1, even when the coupler and yoke move forwardly away from the front wedge member 25 upon the application of draft forces.

From the foregoing description, it will be seen that under the action of draft forces the housing 13 is held stationary by the key 17, the ends of which are received in the slots 18 in cheek plates 19, so that said key functions as front stop means for the rearwardly disposed mechanism 12, and the coupler pulls the yoke 9 forwardly through the connecting draft key 10, moving the rear follower portion 26 and associated central wedge portion 25 between the wedge blocks 24, compressing the springs 23, thereby actuating only the rear mechanism as the coupler and yoke move away from the forward mechanism which thereby is idle under the action of draft forces, so that only one-half, or a portion, of the total capacity of the double-ended gear is utilized, and the coupler moves only one-half or a portion of the total permissible or normal compression of the gear.

Under the action of buffing forces, however, the drawbar or coupler stem 8 engages the front follower 26, pushing the wedge portion 25 into the front opening of the housing 13, and simultane-

ously moving said housing rearwardly over the rear wedge 25, because of the rearward elongation of the slots 18 in the cheek plates 19 permitting the key 17 to travel rearwardly, so that a full compression of said gear on buff is permitted, thereby providing for not only an increased buffing capacity, but for a drawbar travel equal to the sum of the travel permitted by the friction elements at each end of the gear. Although, for convenience and economy in manufacture, the gear is preferably made so that the travel and capacity provided by each cushioning device 12 is identical, yet this is not essential in accordance with the broad aspects of the invention, so that the capacities and travels of the two ends of the gear may be either equal or different, as desired.

Referring now to the embodiment of my invention illustrated in Figures 3 and 4, a construction is there disclosed which is quite similar to that of the preceding embodiment and involves the sills 1 connected by a combined rear lug or backstop and center filler casting 2 and a combined striking casting and sill tie member 3, said latter casting being formed with integral cheek plates 4 slotted at 5 for receiving the draft key 10 which connects the drawbar or coupler stem 8 to the vertical yoke 9.

As in the previous embodiment, a double-ended draft gear 11 is employed comprising a housing 13 receiving in each end a cushioning device 12 and slotted, as indicated at 16, to receive a supporting and connecting draft key 17, the ends of which are received in slots 18 in cheek plates 19 and/or the sills 1 of the vehicle.

The cushioning mechanism at each end of the housing 13 in the present embodiment preferably involves the formation of the housing double bell-mouthed, that is, with inwardly converging friction surfaces 24 and inwardly disposed but preferably correspondingly inclined friction surfaces 24^b with a shouldered portion therebetween. Cooperating with the friction surfaces and shouldered portions on the shell or housing 13 are friction shoes or wedges 25 provided with correspondingly inclined friction surfaces engaging the friction surfaces 24^a and 24^b on the shell and provided with shouldered portions therebetween for cooperating with the correspondingly shouldered portions on the housing and limiting outward movement of said friction elements with respect to the housing, when assembled therewith.

In order to urge the friction elements 25 into engagement with the friction surfaces on the housing 13, resilient means 23, preferably in the form of curved leaf springs, are provided between the friction elements 25 at each end of the housing. Said leaf springs preferably involve two sets at each end bowed or curved concavely toward the adjacent friction elements 25. The outer or large end of the wedges 25 are engaged by a front follower 26^a at the front or outer end of the housing and a rear follower 26^b at the rear or inner end of the housing.

From the foregoing description, it will be apparent that the follower 26^a will not stay in place because of its relation with the wedge blocks 25 when the drawbar 8 and housing 9 move forwardly under the action of draft forces. Because of this, the cheek plates 4 are desirably provided with lugs or diminutive front stop means 32 preferably normally spaced slightly from the front surface of said follower 26^a to facilitate assembly, but normally disposed adjacent thereto so that said follower is maintained in approximately the proper relation with respect to the housing 13.

and associated mechanism when the coupler and yoke move forwardly under the action of draft forces. In the present embodiment, the lug portions 32 are shown separated by a bifurcation of the cheek plates 4^a to permit the necessary rearward movement of the key 10^a for a full compression of the gear 11^a, but it will be understood that, if desired, such movement may be provided for by extending the key slot in the drawbar forwardly 10 to provide for such movement so that the slot 5^a may terminate forwardly of the lugs 32.

From the foregoing disclosure, it will be seen that the operation of the embodiment shown in Figures 3 and 4 is substantially the same as that shown in Figures 1 and 2, the rearward mechanism 12^a only being actuated upon forward movement of the yoke 9^a when the associated coupler is subjected to draft forces because of the key 17^a which acts as front stop means. Under the action of buffing forces, however, the friction wedges 25^a are pushed into the front of the housing 13^a, while the housing moves rearwardly due to the elongation of the slots 18^a in the cheek plates 19^a and closes over the rear friction wedges 25^a, resulting in a complete closure of the gear and development of the full cushioning capacity upon a complete buffing movement of the drawbar. In this way, as in the previous embodiment, more or double the cushioning capacity and drawbar movement is provided for the absorption of buffing forces than for the absorption of draft forces.

From the foregoing disclosure, it will be seen that I have provided railway draft rigging shown in one form associated with a double end or selective travel gear of the self-contained type, or in which the end followers cannot separate from the gear itself, and in the other, one in which there are separate or loose followers in combination with a vertical yoke key-connected to a drawbar or coupler stem, the gears of both forms being supported and connected to the sills by horizontal means extending through the housings thereof and functioning as front stop means for the rear cushioning mechanism, whereby a greater cushioning capacity and movement is provided for under the action of buffing than under the action of draft forces. In the form in which separate loose followers are used, diminutive lugs or front stop means are provided, normally spaced from the front face of the front follower, to keep said follower from floating away from the draft gear when the coupler shank is drawn out under pull. Secondarily, of course, such lugs serve as an emergency front stop should the transverse housing key or any cooperating parts fail. In the first form of the invention, it will also be apparent that the key which connects the drawbar and yoke, although primarily a tension connection between said members, is secondarily a support for both and an emergency means should the yoke or anything else in the tension series break.

Although preferred embodiments of my invention have been illustrated, it will be understood that modifications may be made within the spirit and scope of the appended claims.

I claim:—

1. In railway draft rigging, in combination with draft sills, a drawbar, a vertical yoke, means for operatively connecting the drawbar and yoke for the transmission of draft forces, cushioning means embraced by said yoke and comprising a housing open, and receiving friction elements urged thereagainst by resilient means disposed therebetween, at each end, followers engaging the outer ends of said friction elements at each end of the cushioning means, front stop means for limiting forward movement of the housing to effect compression of the cushioning mechanism in the rear end of the housing on draft, backstop means engaging the rear follower, and diminutive front stop means normally spaced forwardly of the front follower a slight amount to merely serve to keep the front follower from floating away from the cushioning means when the drawbar moves forwardly under the action of draft forces. 5
2. In railway draft rigging, in combination with draft sills, a drawbar and vertical yoke-acting means, a friction draft gear comprising a column member provided with a horizontal longitudinally extending slot disposed adjacent the central portion thereof, a set of friction elements cooperating with said column member at each end, a follower engaging said elements at each end of the gear, stop means normally spaced forwardly of the front follower for preventing undesired displacement thereof and stop means for preventing rearward movement of the rear follower from normal position, said yoke-acting means embracing the gear and followers, a key passing through the slot in the column member and corresponding slots in the sills to act as front stop means for said column member, said sill slots terminating at the normal position of the front edge of the keys, so that the yoke-acting means actuates only the rear 10 friction elements on draft, and rearwardly elongated to permit rearward movement of the key so that the friction elements at both ends of the gear are actuated when the drawbar is subjected to buffing forces. 15
3. Cushioning mechanism comprising housing means involving a pair of walls spaced to snugly fit between the arms of a vertical yoke and another pair of walls spaced to snugly fit between associated draft sills, said housing means being open, and said last-mentioned pair of walls provided with outwardly diverging friction surfaces, at front and back ends, a set of friction elements with cooperating corresponding friction surfaces disposed in said housing means at each end, resilient means at each end disposed between said friction elements for urging them into engagement with said housing means, and followers engaging the outer ends of said friction elements, the walls of said housing means provided with said friction surfaces being slotted to receive a key adapted to connect said housing means with said sills. 20
4. In a railway draft rigging, in combination with draft sills, a drawbar, a vertical yoke, means for operatively connecting the drawbar and yoke for the transmission of draft forces, cushioning mechanism embraced by said yoke and comprising a housing open, and receiving friction elements and resilient actuating means, at each end, front and rear followers associated with said friction elements, stop means disposed between the friction elements at the ends of the mechanism for limiting forward movement of the housing to effect compression of the cushioning means at the rear end of the housing on draft, backstop means for said cushioning mechanism, and means serving to keep the front follower from floating away from the draft gear when the drawbar moves forwardly under the action of draft forces. 25
5. In railway draft rigging, in combination with draft sills, a drawbar, a vertical yoke, means for operatively connecting the drawbar and yoke for the transmission of draft forces, cushioning mechanism embraced by said yoke and comprising a housing open, and receiving friction elements and resilient actuating means, at each end, front and rear followers associated with said friction elements, stop means disposed between the friction elements at the ends of the mechanism for limiting forward movement of the housing to effect compression of the cushioning means at the rear end of the housing on draft, backstop means for said cushioning mechanism, and means serving to keep the front follower from floating away from the draft gear when the drawbar moves forwardly under the action of draft forces. 30

- ing a housing open, and receiving friction elements and actuating resilient means, at each end, front and rear followers associated with said friction elements, a key extending through said housing between the friction elements and resilient means at the ends thereof, the ends of said key being received in slots in said sills to function as stop means for said housing, to effect actuation of the friction elements and resilient means at the rear end thereof when the drawbar is subjected to draft forces, said sill slots being extended rearwardly of the normal position of the rear edge of said key to permit actuation of the entire mechanism on buff, backstop means for said cushioning mechanism, and means serving to keep the front follower from floating away from the cushioning mechanism when the drawbar moves forwardly under the action of draft forces.
6. In railway draft rigging, in combination with draft sills, a drawbar, a yoke, means for operatively connecting the drawbar and yoke for the transmission of draft forces, cushioning mechanism embraced by said yoke and comprising a housing open, and receiving friction elements and resilient actuating means, at each end, front and rear followers associated with said friction elements, stop means disposed between the friction elements at the ends of the mechanism for limiting forward movement of the housing to effect compression of the cushioning means at the rear end of the housing on draft, backstop means for said cushioning mechanism, and means serving to keep the front follower from floating away from the draft gear when the drawbar moves forwardly under the action of draft forces.
7. Cushioning mechanism comprising housing means involving a pair of walls spaced to snugly fit between the arms of vertical yoke-acting means and another pair of walls provided with outwardly diverging friction surfaces at their ends, spaced to snugly fit between associated sills, and slotted to receive a key adapted to connect said housing means to said sills, friction elements with corresponding friction surfaces engaging said diverging friction surfaces on the housing means, resilient means acting on said friction elements to maintain said frictional engagement, and follower means engaging the outer ends of said friction elements.
8. Cushioning mechanism comprising housing means involving a pair of walls spaced to snugly
- fit between the arms of a vertical yoke and another pair of walls spaced to snugly fit between associated draft sills, said last-mentioned pair of walls being adapted to cooperate with friction mechanism in said housing means at front and back ends, mechanism disposed in said housing means at both ends for cooperating with said last-mentioned pair of walls and including friction elements, resilient means, and follower members having portions adapted to extend in the adjacent ends of said housing means for actuating said mechanism, the walls of said housing means adapted to cooperate with said friction mechanism being slotted to receive a key adapted to connect said housing means with said sills.
9. In railway draft rigging, in combination with draft sills, a coupler, a vertical yoke, means for operatively connecting the coupler and yoke for the transmission of draft forces, cushioning mechanism embraced by said yoke and comprising a housing adapted to receive friction elements and resilient actuating means at each end, front and rear follower members associated with said friction elements, stop means disposed intermediate the ends of the cushioning mechanism for limiting forward movement of the housing to effect compression of the cushioning means at the rear end of the housing on draft, backstop means for said cushioning mechanism, and means for maintaining the forward friction elements and associated follower member in position relative to the housing when the coupler moves forwardly under the action of draft forces.
10. In railway draft rigging, in combination with draft sills, a coupler, a yoke, means for operatively connecting the coupler and yoke for the transmission of draft forces, cushioning mechanism embraced by said yoke and comprising a housing open and receiving friction elements and resilient actuating means at each end, front and rear follower-acting means associated with said friction elements, stop means disposed rearwardly of the forward end of said cushioning mechanism for limiting forward movement of the housing to effect compression of the cushioning means at the rear end of the housing on draft, backstop means for said cushioning mechanism, and means for preventing forward movement of said front follower-acting means upon draft movement of the coupler.

DONALD S. BARROWS.
